UNITED STATES PATENT OFFICE.

JOHN T. CRAMPTON, OF PAWNEE CITY, NEBRASKA, AND DAYTON PRICE, OF NEMAHA COUNTY, KANSAS; SAID PRICE ASSIGNOR TO SAID CRAMPTON.

WAGON-REACH.

SPECIFICATION forming part of Letters Patent No. 715,994, dated December 16, 1902.

Application filed April 15, 1902. Serial No. 102,989. (No model.)

To all whom it may concern:

Be it known that we, JOHN T. CRAMPTON, residing at Pawnee City, in the county of Pawnee and State of Nebraska, and DAYTON 5 PRICE, residing in Nemaha county, State of Kansas, citizens of the United States, have invented certain new and useful Improvements in Wagon-Reaches, of which the following is a specification.

10 Our invention relates to wagon-reaches, and more especially to an adjustable reach to permit the length of the truck to be varied, and thus accommodate wagon-boxes and hay or stock racks of varying lengths.

15 A further object is to produce a device of this character of simple, strong, durable, and cheap construction.

To these ends the invention consists in certain novel and peculiar features of construction and combinations of parts, as hereinafter described and claimed, and in order that the invention may be fully understood reference is to be had to the accompanying drawings, in which—

25 Figure 1 is a perspective view showing in full lines the rear portion of a wagon-reach embodying our invention and the front portion of the rear hounds, and in dotted lines the rear axle, bolster, and rear portion of said 30 hounds. Fig. 2 is a central longitudinal section of the sleeve portion of the reach. Fig. 3 is a top plan view of the front end of the sleeve portion of the reach and of the hounds, the former being shown as arranged previous 35 to its permanent connection to said hounds. Fig. 4 is a perspective view of the front end of the sleeve portion of the reach as arranged after it is permanently secured to the rear hounds, the hounds, however, being omitted.

40 Referring to the drawings in detail, where like reference characters designate corresponding parts, 1 designates the rear axle, and 2 the rear bolster, superposed with relation to the axle and secured thereto in the 45 usual or any preferred manner. 3 designates the rear hounds, secured to and between said axle and bolster and converging forwardly to the opposite sides of the sleeve portion 4 of the reach, said sleeve portion fitting at its rear end 50 between the axle and bolster and having upwardly-projecting and depending perforated

flanges 5 and 6, bearing, respectively, against the rear sides of the bolster and axle, and secured rigidly in any suitable manner upon said sleeve portion 4 is a collar 7, having upwardly-projecting and depending perforated flanges 8 and 9, bearing, respectively, against the front sides of the bolster and axle, said bolster and axle being clamped rigidly between flanges 5 and 8 and 6 and 9 and upon the 55 sleeve portion 4 by means of bolts 10, extending through the bolster and axle, nuts 11 engaging the rear ends of said bolts. At its front end said sleeve portion is provided with laterally-projecting bottom flanges 12 and top 60 flanges 13. The former are provided at the middle of their outer edges with strap extensions 14, and the flanges 13 are each provided at their outer corners with shorter strap extensions 15. The front ends of the hounds bear 65 against the outer sides of the front end of the sleeve portion between flanges 12 and 13 thereof and are so secured by bending the extensions 15 down against the outer edges and up against the under side of the bottom flanges 70 75 12, while the strap extensions 14 of the bottom flanges are bent upwardly against the outer edges of the hounds and down upon the top flanges, their ends overlapping, as shown. When thus arranged, bolts or rivets 16 are fitted down through the top flanges, the hounds, the bottom flanges, and the strap extensions 15. 80

The front portion of the reach, numbered 17 and adapted to be secured in the usual manner to the front portion of the truck, 85 (not shown,) is provided with a series of vertical perforations 18 near its rear end, which end fits telescopically in sleeve portion 4 and is united reliably to the latter by means of bolt 19, extending down through the overlapping ends of strap extensions 14 and sleeve portion 4 and is engaged at its lower end by a nut 20. By this arrangement it is obvious that to extend or contract the length of the reach it is only necessary to remove bolt 19 90 and adjust the rear portion of the truck forwardly or rearwardly the desired distance, when bolt 19 is again secured in the manner explained, but of course extends through a different hole 18. 95

100 By the construction described it will be apparent that an extensible and contractible

reach is provided which embodies the features of advantage enumerated as desirable and that the means employed for clamping the rear end of the sleeve portion to the rear bolster and axle and the front end of the sleeve portion to the hounds tends to resist any independent longitudinal straining movement and make the structure strong and rigid and that by interlocking the strap extensions by fitting those of the bottom flanges between those of the upper flanges the bolt 19 is relieved of considerable strain which would otherwise be imposed upon it if there was any lost motion caused by the bolts or rivets 16 fitting loosely through the registering holes of the top and bottom flanges and the hounds and strap extensions 15.

From the above description it will be apparent that we have produced an extensible reach which obviously may be modified in some minor particulars without departing from the principle of construction involved.

Having thus described the invention, what we claim as new, and desire to secure by Letters Patent, is—

1. An adjustable reach for wagon-trucks, comprising a rear sleeve portion, a front portion fitting telescopically in the rear portion, means for securing said portions at different positions of adjustment, top and bottom flanges projecting laterally from the sleeve

portion to embrace the upper and lower sides of the rear hounds and bolted to the latter, and strap extensions for said top and bottom flanges, the strap extensions of one set of said flanges fitting between the strap extensions of the other set of flanges, and bearing against the outer edges of the hounds.

2. An adjustable reach for wagon-trucks, comprising a rear sleeve portion, a front portion fitting telescopically in the rear portion, means for securing said portions at different positions of adjustment, top and bottom flanges projecting laterally from the sleeve portion to embrace the upper and lower sides of the rear hounds and bolted to the latter, and strap extensions for said top and bottom flanges, the strap extensions of one set of said flanges fitting between the strap extensions of the other set of said flanges and bearing against the outer edges of the hounds, and bolts extending through said top and bottom flanges, the interposed hounds and certain of said strap extensions.

3. An adjustable reach for wagon-trucks, comprising a rear sleeve portion, a front portion fitting telescopically in the rear portion, means for securing said portions at different positions of adjustment, top and bottom flanges projecting laterally from the sleeve

portion to embrace the upper and lower sides of the rear hounds and bolted to the latter, and strap extensions for said top and bottom flanges, the strap extensions of one set of said flanges fitting between the strap extensions of the other set of flanges and bearing against the outer edges of the hounds, certain of said strap extensions overlapping each other, and secured together by the means employed for uniting the front and rear portions of the reach together.

4. An adjustable reach for wagon-trucks, comprising a rear sleeve portion, a front portion fitting telescopically in the rear portion, means for securing said portions at different positions of adjustment, top and bottom flanges projecting laterally from the sleeve

portion to embrace the upper and lower sides of the rear hounds and bolted to the latter, and strap extensions for said top and bottom flanges, the strap extensions of one set of said flanges fitting between the strap extensions of the other set of flanges and bearing against the outer edges of the hounds, and bolts extending through said top and bottom flanges, the interposed hounds and certain of said strap extensions, certain of said strap extensions overlapping each other, and secured together by the means employed for uniting the front and rear portions of the reach together.

5. An adjustable reach for wagon-trucks, comprising a rear sleeve portion, having upwardly-projecting and depending flanges at its rear end to bear respectively against the rear sides of the rear bolster and axle, a collar secured upon said sleeve portion and provided with flanges to bear against the front sides of the rear bolster and axle respectively, bolts to extend through the bolster and the axle and adapted to connect the upper flanges together and the lower flanges together, a front portion fitting telescopically in the rear portion, means for securing said portions at different positions of adjustment, top and bottom flanges projecting laterally from the sleeve portion to embrace the upper and lower sides of the rear hounds and bolted to the latter, and strap extensions for said top and bottom flanges, the strap extensions of one set of said flanges fitting between the strap extensions of the other set of flanges, and bearing against the outer edges of the hounds.

In testimony whereof we affix our signatures in the presence of two witnesses.

JOHN T. CRAMPTON.
DAYTON PRICE.
